United States Patent Office.

HUBERT BURGESS, OF OAKLAND, CALIFORNIA.

Letters Patent No. 102,766, dated May 10, 1870.

IMPROVEMENT IN PENCIL-SHARPENERS.

The Schedule referred to in these Letters Patent and making part of the same.

To all whom it may concern:

Be it known that I, HUBERT BURGESS, of the city of Oakland, county of Alameda, State of California, have invented a Guide for Sharpening Pencils, and I do hereby declare the following description and accompanying drawings are sufficient to enable any person skilled in the art or science to which it most nearly appertains to make and use my said invention and improvements without further invention or experiment.

My invention relates to a device to be used for guiding the blade of a knife in sharpening pencils; and

It consists of a cylinder, or other suitably-shaped block of wood or metal, which is cut beveling on one side only.

A hole is made longitudinally through the block, through which the pencil is thrust. A loosely revolving spring is arranged about the hole, which clasps the pencil and allows it to revolve inside the block.

A knife is used to sharpen the pencil, the bevel of the block guiding it in cutting the wood and sharpening the point.

In order to more fully illustrate and explain my invention, reference is had to the accompanying drawings forming a part of this specification, in which—

Figure 1 is a side view.

Figure 2 is a longitudinal section.

A represents a cylindrical or other shaped block of wood, metal, hard rubber, or other suitable material, having sufficient solidity to prevent the sharp blade of a knife from readily cutting it.

This block of wood or other material is perforated, longitudinally, with a hole, *a*, which is of sufficient diameter to easily admit the largest size of pencil or crayon which it may be necessary or desired to sharpen.

Inside of the hole *a*, at any convenient point, I place a loosely moving clasp-spring, *b*, shown at fig. 2. In the present instance, this spring consists of a small roll of spring metal, having a flange at each end, which confines it inside of a small chamber. This chamber is grooved out around the hole *a* of just sufficient width to admit the spring and allow it to move freely around.

The spring must be capable of expansion, so as to admit the different sizes of pencils and clasp each firmly, so as to cause them both to turn in conjunction inside the cylinder or other block *A*.

The block *A* is beveled off on one side, *e*, so as to furnish a guide for the knife in giving a regular and proper taper to the point of the pencil, which is turned in the block by the fingers to present its different sides to the knife in succession.

The device is cheap, useful, and convenient, and can be used by any persons, even children.

Having thus described my invention,

What I claim, and desire to secure by Letters Patent, is—

1. The beveled cylinder or block *A*, with its central hole *a*, substantially as and for the purpose above described.

2. In combination with the beveled cylinder or block *A*, perforated as described, the loosely revolving extensible clasp-spring *b*, for the purpose set forth

In witness whereof I have hereunto set my hand and seal.

HUBERT BURGESS. [L. S.]
